UNITED STATES PATENT OFFICE.

J. FRANK ANDRES, OF ST. LOUIS, MISSOURI, ASSIGNOR TO UNITED STATES SAFETY GAS MACHINE COMPANY, OF ST. LOUIS, MISSOURI, A CORPORATION OF MISSOURI.

CARBURETER.

1,106,070.

Specification of Letters Patent.

Patented Aug. 4, 1914.

Application filed November 13, 1912. Serial No. 731,049.

To all whom it may concern:

Be it known that I, J. FRANK ANDRES, a citizen of the United States residing at the city of St. Louis, State of Missouri, have invented certain new and useful Improvements in Carbureters, of which the following is a specification.

This invention relates to improvements in carbureters and embodies novel improvements in the carbureter disclosed in my United States Letters Patent No. 876,678, granted January 14, 1908.

The primary object of the present invention is to provide a carbureter in which air under pressure enters at the bottom of same, passes upwardly through a serpentine or zig-zag course between a series of partitions or diaphragms, and mixes with the vapors of a hydrocarbon, which enters at the top of the carbureter and flows downwardly by gravity through the same course, the mixture being drawn from the top of the carbureter and used for heating, cooking, and illuminating purposes, the novelty residing in the provision of improved partitions or diaphragms for the carbureter.

With this object in view, the present invention consists in the provision of a carbureter in which there is arranged a series of partitions or diaphragms, each of which is formed of cloth or other suitable fabric and having an opening at one point therein, the openings in the partitions or diaphragms being arranged in staggered relation, so as to produce a serpentine or zigzag course for the air ascending from the air inlet to the service pipe and, also, for the hydrocarbon descending from the hydrocarbon inlet to the bottom of the carbureter, and the cloth or other fabric being coated or filled to such extent with any organic substance, such as sodium silicate (water glass) or other suitable filler, impervious to the hydrocarbon used that the threads thereof will be hydrocarbon-proof and the hydrocarbon will merely percolate through each partition or diaphragm and hang in drops on the lower side thereof, permitting the hydrocarbon to evaporate from both sides of each partition or diaphragm.

Further, the present invention consists of the novel features of construction and arrangement of parts hereinafter more fully described and pointed out in the claims.

In the accompanying drawings forming part of this specification, in which like numbers of reference denote like parts wherever they occur, Figure 1 is a vertical sectional view of a carbureter equipped with a series of the improved partitions or diaphragms embodying the present invention; Fig. 2 is a perspective view of one of the partitions, showing the upper side thereof; and Fig. 3 is a perspective view of same, showing the lower side thereof.

In the drawings, 1 designates the carbureter which is preferably formed of an upright cylindrical tank, the lower end being closed by a bottom plate 2, which is concave so as to slope toward the opening 3 for draining the carbureter, which opening is closed by a removable plug 4. The upper end of the carbureter 1 has a ring 5 shrunk or otherwise secured upon same, said ring having an angle-iron cross-section with an outwardly flaring flange 6 to which the cover 7 of the carbureter is fastened by bolts 8 or other suitable means.

The air under pressure enters the carbureter through an inlet pipe 9 at a point adjacent to the bottom 2, and the mixture is drawn from the upper end of the carbureter through a service pipe 10. Located within the carbureter intermediate the inlet pipe 9 and the service pipe 10 is a series of horizontally-disposed partitions or diaphragms 11. Each partition or diaphragm 11 is formed of a piece of cloth, such as cheese cloth or any other suitable fabric, that is stretched over the upper edge of a hoop 12 like a drum head, leaving an opening 13 adjacent to one side for an air passage, the edge of the cloth being stretched over the side of the hoop and being fastened by tacks 14 or other suitable means. The hoop 12 is preferably formed of wood, though, of course, may be formed of any desired material, and has its ends tacked or otherwise secured together so that the hoop will be of such size when the cloth is stretched thereupon that same will fit snugly within the carbureter. The partition or diaphragms 11 are placed one on top of another within the carbureter 1 with the openings 13 in the former arranged in staggered relation, so as to produce a serpentine or zigzag passage for the air from the inlet pipe 9 to the service pipe 10, the lowermost partition or dia-

phragm 11 being supported on a bell-shaped member 15 resting on the bottom 2, which member receives the air from the inlet pipe 9 and contains an opening 16 to allow the air to pass upwardly through the circuitous course formed by the partitions or diaphragms 11 as just described. Another member 17, which is preferably bell-shaped, rests upon the uppermost partition or diaphragm 11 and affords a weight which helps to hold the partitions or diaphragms in place, same containing an opening 18 to allow the hydrocarbon to flow from the pipe 19 into the upper end of the zigzag passage 15 for the air and, also, to permit the mixture formed within the zigzag passage in the manner hereinafter described to pass into the chamber 20 in the upper end of the carbureter between the member 17 and the cover 7, from which chamber the mixture escapes through the service pipe 10. The hydrocarbon which is delivered from the pipe 19 into the carbureter flows through the opening 18 in member 17 and falls upon the upper partition or diaphragm 11, thence flows over and across the upper partition or diaphragm toward the opening 13 in same through which it flows and falls upon the second partition or diaphragm, then over and across the second partition or diaphragm toward the opening 13 in same, and, so on, gravitating through the zigzag passage toward the bottom of the carbureter. The hydrocarbon descending through the zigzag passage mixes with the air ascending through the same passage, with the result of producing carbureted air or mixture which fills the chamber 20 in the upper end of the carbureter, from which the carbureted air or mixture may be drawn through the service pipe 10 for cooking, heating, and illuminating purposes.

The cloth of each partition or diaphragm 11 is coated or painted with or dipped in liquid glass or other suitable filler impervious to the hydrocarbon used and of a consistency that, when set, will render the threads of the cloth hydrocarbon-proof and will fill the interstices between the threads to such extent that some of the hydrocarbon will percolate therethrough and hang in drops upon the lower side thereof in the most perfect position for evaporation by the air passing therebeneath. In this way, the hydrocarbon is permitted to evaporate from both sides of each partition or diaphragm, thereby doubling the evaporating surface. The coating or filler provides each cloth partition or diaphragm 11 with a surface over which the hydrocarbon flows readily in descending through the zigzag passage in the manner hereinabove described, and prevents the cloth from stretching and sagging and the hydrocarbon from standing in a pool upon the partition or diaphragm and from

running through the partition or diaphragm as occurs when cloth without this coating or filler is used.

As a means for preventing the pressure of the air traveling upwardly through the zigzag passage formed by the partitions or diaphragms 11 from causing the latter to bulge, each partition or diaphragm has a string or cord 21 or the like or a plurality of such strings or cords stretched across the lower side of same so as to form somewhat of a network, as best seen in Fig. 3, said string or strings being sewn to the cloth 11 or otherwise attached to the lower edge of the hoop 12. By this arrangement, when the partitions or diaphragms 11 are assembled one on top of another within the carbureter, the strings 21 on the lower side of each partition or diaphragm extend across the upper side of the cloth partition or diaphragm therebeneath and thereby prevents the pressure of the air from causing either the latter to bulge upwardly and contact the former, or the former to sag and touch the latter. In this way the zigzag passage for the air and hydrocarbon is prevented from becoming obstructed. It will be obvious that it is unnecessary to provide the bottom partition or diaphragm 11 with the string or strings 21.

It will be readily observed that the partitions or diaphragms 11 are simple and inexpensive to manufacture and that same greatly reduce the weight of the carbureter. Furthermore, when the partitions or diaphragms 11 are forced or driven together one on top of another within the carbureter, the wooden hoops 12 form practically a continuous wood lining which prevents the vapors from coming in contact with the metallic shell of the carbureter, thus preventing the formation of frost during excessive evaporation. One great advantage arising from the use of these improved partitions or diaphragms resides in the fact that the efficiency of the carbureter is greatly increased thereby, for the reason that by forming the partitions or diaphragms of cloth and wood, these materials will not lower the temperature within the carbureter in times of excessive evaporation as occurs when metallic partitions or diaphragms are used.

From the foregoing, it is believed the operation of the apparatus will be apparent and needs no further description.

I claim:

1. In a carbureter, the combination of a series of partitions or diaphragms within same, each comprising a hoop having cloth or other fabric stretched across the upper side thereof so as to leave an opening adjacent to one side thereof and string or the like stretched across the lower side of same, said partitions or diaphragms being arranged one on top of another with the open-

- ings therein in staggered relation to form a circuitous passage, and means for circulating the hydrocarbon and air through the circuitous passage in opposite directions.
- 5 2. A partition or diaphragm for a carbureter comprising a hoop having cloth or other fabric stretched across the upper side thereof so as to leave an opening adjacent to one side thereof and string or the like 10 stretched across the lower side of same.
3. A partition or diaphragm for a carbureter comprising a hoop having cloth or other fabric stretched across the upper side thereof so as to leave an opening adjacent 15 to one side thereof and string or the like stretched across the lower side of same, the cloth or other fabric having a coating or filler, which is impervious to the hydrocarbon and fills the interstices of same to such 20 extent that the hydrocarbon will percolate therethrough and hang in drops on the lower side thereof.
4. In combination with a carbureter having an air-inlet at or adjacent to the bottom 25 thereof and an outlet and a supply pipe at or adjacent to the top of same, of a series of partitions or diaphragms intermediate the inlet and outlet, each partition or diaphragm comprising a hoop having cloth or 30 other fabric stretched across the upper side
- thereof so as to leave an opening adjacent to one side of same and string or the like stretched across the lower side thereof, said partitions or diaphragms being arranged one on top of another with the openings 35 therein in staggered relation to form a circuitous passage for the hydrocarbon and the air, and the cloth or other fabric having a coating or filler, which is impervious to the hydrocarbon and fills the interstices of the 40 former to such extent that the hydrocarbon will percolate therethrough and hang in drops on the lower side thereof.
5. In a carbureter, a series of partitions each composed of a hoop having fabric 45 stretched across its upper side and fabric engaging means extending across its lower side, the hoops being arranged in superimposed relation to cause said means of an upper partition to limit the extent of upward 50 movement of the fabric of the lower adjacent partition by engagement with the fabric.

In testimony whereof I hereunto affix my signature in the presence of two witnesses. 55

J. FRANK ANDRES.
